MOTOR PUMP UNIT

Frederick Kraissl, Jr., 244 Kinderkamack Road,
North Hackensack, N.J.

Filed Mar. 28, 1962, Ser. No. 69,465

Term of patent 14 years

(Cl. D65—1)

FIG. 1.

FIG. 1 is a perspective view of a motor pump unit showing my new design; and FIG. 2 is a perspective view taken diametrically opposite that shown in FIG. 1.

The end of the motor housing is substantially flat and unornamented.

I claim:

The ornamental design for a motor pump unit, as shown and described.
